LOOSE-LEAF BINDER

Alfred Gilbert, London, England

Application July 31, 1946, Serial No. 687,266
In Great Britain April 4, 1945Section 1, Public Law 690, August 8, 1946
Patent expires April 4, 1965

3 Claims. (Cl. 129—41)

1

This invention concerns improvements in or relating to loose leaf binders, and the invention has especial reference to thong and post binders.

In thong binders as at present made it is usual to secure one set of ends of the thongs to one of the covers of the binder and to secure the other set of thong ends to a tensioning bar housed within the other cover of the binder, such bar being adjustable relatively to the cover by means of operating mechanism comprising a nut or equivalent part fixed upon the bar and working upon a long screw housed within the thickness of the cover extending parallel to the top and bottom edges of the cover, such screw being mounted for rotation, but not axial movement in bearings in the cover. One end of the said screw is disposed adjacent the free end of the binder cover (that is, the end opposite to the hinged end) and is adapted to receive a detachable crank handle or a key by which the screw may be rotated to adjust the said cross bar, through the co-operation of its nut with the said screw, relatively to the binder cover in order to tighten or slacken the binding thongs.

In a post binder it is usual to employ a binding bar (which may form an integral part of one of the covers of the binder or may be a separate element) which is furnished with holes into or through each of which projects a binding post which may be locked in the hole, for example, by being gripped by a locking slide slidably carried by the binding bar and adapted to be slid longitudinally relatively to the latter by operating mechanism including screw and nut means. In these post binders the said screw and nut means comprise a screw threaded spindle mounted in the binding bar and co-operating with a screw threaded nut or nut-like part, the spindle being operated by a detachable key adapted to be engaged with one end of the spindle which is disposed within one end of the binding bar.

The present invention is to an operating mechanism for the clamping or locking means for loose leaf binders and has for its object to eliminate the use in loose leaf binders of detachable handles or keys for actuating the said operating mechanism, for the use of detachable handles or keys has very serious disadvantages. For example, if the handle or key is not available the binder cannot be opened or, if already opened, cannot be locked in the leaf retaining or closed position; there is a grave danger of the handle or key being lost or temporarily misplaced; there is usually some delay caused by the manipulation of the handle or key necessary to engage it with

2

the said screw of the operating mechanism; and also the end of the handle or key engaging the screw or the end of the screw or both these parts become worn and inefficient or, where these parts are provided with a hole, such hole becomes choked with fluff or the like thus rendering it necessary to clear the hole before the handle or key can be engaged with the screw.

In order that the nature of the invention may 10 be more thoroughly understood and the method of carrying same into effect may be more readily carried into practice, the invention is hereinafter described with reference to the accompanying drawings, and by way of example, as applied to 15 thong binders and post binders. In the drawings:

Figure 1 is a part sectional plan view of the upper cover of a thong binder embodying this invention;

20 Figure 2 is a section on line 11—11, Figure 1;

Figure 3 is an exploded perspective view showing in detail the operating mechanism for the cover-adjustment means employed in the binder to which the cover shown in Figures 1 and 2 be-

25 longs;

Figures 4 and 5 are fragmentary perspective views further illustrating a portion of the operating mechanism shown in Figures 1 to 3;

30 Figure 6 is a fragmentary perspective view showing the invention applied to one form of post binder;

Figure 7 is a part sectional plan view of the binding bar of the upper cover of the binder shown in Figure 6; and

35 Figure 8 is a part sectional elevation on line VIII—VIII, Figure 7.

Referring to Figures 1 to 5 of the accompanying drawings it will be seen that the loose leaf thong binder, the upper cover of which is there 40 illustrated, is of the kind which comprises upper and lower covers between which the loose leaves are clamped, and wherein the covers are drawn together and on to the loose leaves by thongs which pass through the leaves and over guide 45 rollers, or equivalent devices, supported in binding bars with which the covers are provided. The upper binder cover comprises a binding bar 1 to which the main part of the cover 2 is hinged at 3 and 4. Two spaced parallel thongs 50 5 and 6 are provided and these thongs pass through slots 7 in the binding bar 1 and over rollers (not shown) carried by this bar. The thongs also pass through the leaves between the covers of the binder and over rollers in the binding bar of the lower cover of the binder and are 55

fixed, at their lower ends, to the said lower cover.

The upper end portions of the thongs 5 and 6 are housed within the upper cover of the binder, the part 2 of which cover is made hollow to receive the thongs and the mechanism associated therewith and subsequently to be described. The extremities 8 and 9 of the thongs 5 and 6 are secured to a cross bar 10 extending perpendicularly between them and having a nut 11 fixed centrally thereto and provided with a bore 12 perpendicular to the bar 10. The said bore is internally screw threaded for engagement with a rotary operating screw 13 passing through the nut and rotatably mounted adjacent its opposite ends respectively in brackets 14 and 15 secured to the bottom wall 16 of the cover part 2 so as to be housed within the latter. Although the screw 13 is rotatable in the bearings 14 and 15 it is restrained against axial movement in these bearings, this being effected in the example shown, by providing the screw with an enlarged collar 17 engaged between the two end portions 18 and 19 of the bracket 15.

The binder is closed or opened respectively to lock the leaves therein or to release the leaves for removal, by rotating the screw 13 in the appropriate direction which causes the cross bar 10, through the medium of the nut 11, to be moved along the screw 13 in one direction or the other depending upon the direction of rotation of the screw.

The parts of the thong binder so far described are constructed more or less along the normal lines.

In applying the present invention to a thong binder of the kind above referred to the screw 13 is provided with a reduced plain extension 20 (see particularly Figures 2 and 3) which terminates at a distance from the outer free end 21 of the binder cover part 2. Upon the screw extension 20 is mounted a coupling element which, in the example illustrated, is in the form of a sleeve or tube 22 which is capable of being slid axially along the extension 20. The extent to which the sleeve 22 may be slid upon the extension 20 is limited by a fixed radial pin 23 carried by the screw extension 20 and working in a longitudinal slot 24 provided in the sleeve 22. The pin 23 also provides a connection between the screw extension 20 and the sleeve 22 so as to ensure that the extension will rotate with the sleeve.

A friction device is provided to restrain the sleeve 22 from too free an axial movement upon the screw extension 20, this friction device conveniently comprising a spring ring 25 mounted in an annular eccentric slot 26 in and adjacent one end of the sleeve 22, the arrangement being such that a portion of the inner periphery of the ring 25 bears resiliently upon the periphery of the screw extension 20.

In the outer end of the sleeve 22, that is the end remote from the screw extension 20, is fixed coaxially the inner end of an outwardly extending pin 26a having a head 27. The pin is secured in the sleeve by means of a cross pin 28 passing through the pin and the sleeve.

Upon the pin 26a, between the outer end of the sleeve 22 and the head 27 of the pin, is mounted an operating lever, knob or button 29 of any suitable form, but which conveniently is of approximately a rectangular parallelepipedon form. This lever knob or button which will, for the sake of brevity, be referred to in this description as a lever is of a size such that it can be housed with-

in a recess 30 provided in the outer perimetrical wall 31 of the hollow cover part 2 of the binder and the recess 30 is of a shape corresponding to that of the lever so that this fits snugly into the recess.

On its inner side the lever 29 is provided with a cylindrical boss 32 of the same external diameter as the sleeve 22 and coaxial with the latter. The inner end of this boss is provided with angularly spaced dog teeth or other suitable teeth or projections 33 adapted to engage in correspondingly disposed and shaped recesses or notches 34 in the adjacent end of the sleeve 22, the teeth 33 and notches 34 constituting together 15 a clutch whereby the lever 29 may be locked to the sleeve 22 for the simultaneous rotation of these two parts as a unit for driving the screw 13.

The lever 29 is also provided with an internal recess 35 coaxial with the pin 26a but of larger 20 diameter than this pin, and upon the pin, within the recess 35, is a helical compression spring 36 abutting at one end the inner side of the head 27 of the pin 26a, and at the other end engaging the inner end of the recess 35 in the lever 25 29 so that the latter is urged inwardly along the pin 26a to engage the teeth or dogs 33 of the lever with the sleeve 22.

Ordinarily the operating lever 29 of the operating mechanism of the binder will be housed entirely in the recess 30 in the free edge of the cover part 2 so that the operating mechanism of the binder is all contained within the boundaries of the binder cover. Such a condition of affairs is shown in full lines in the drawing. Assuming 35 that, with the binder in this condition, it is desired to release the tension of the thongs of the binder, then this is effected by first withdrawing the lever 29 from the recess 30 of the cover and beyond the edge 21 of this cover, i. e. into the 40 position indicated by dot and dash lines, Figure 1.

The recess 30 on the binder cover is open at the upper side of the cover as shown in Figure 4 so as to expose the upper part of the lever to facilitate the latter being engaged manually to effect the withdrawal of the knob or button 29 from the recess 30.

When withdrawn in this way the lever, through the medium of the spring 36 and the pin 26a, draws the sleeve 22 axially outwardly along the 50 screw extension 20, this outward movement of the sleeve being limited by the engagement of the pin 23 of the screw extension with the inner end of the slot 24 of the sleeve.

Having been pulled out sufficiently to clear the 55 edge 21 of the cover 2 the lever 29 may then be rotated about its axis, and by so rotating the lever the sleeve 22, engaged with the lever through the medium of the teeth 33 and notches 34, is also rotated and produces, through the medium 60 of the pin 23, rotation of the screw extension 20, and consequently of the screw 13.

Rotating the screw 13 in this way causes the 65 nut 11 to travel endwise on the screw so that, if the lever is turned in the correct rotational direction, the thongs 5 and 6 of the binder will be slackened to enable leaves to be added or removed from the binder.

If, after the adjustment of the tension of the thongs of the binder, it is desired to return the 70 operating lever 29 into the cover recess 30 but the lever is not properly aligned with the recess 30 in the cover, that is if it is in some position such as that indicated in Figure 4, then the lever can be released from its engagement with the 75 sleeve 22 by pulling it slightly further outwards

to disengage its teeth 33 from the notches 34 of the sleeve 22 (which is held by the pin 23 against further outward movement) whereupon the lever may be turned about its axis (independently of the sleeve) to the requisite extent to move it from its oblique position with respect to the plane of the cover 2 (Figure 4) into the plane of the cover (Figure 5) whereby the lever can then be pushed into the recess 30. In such a case the teeth 33 will not be in engagement with the notches 34 of the sleeve 22, and the teeth will push the sleeve 22 a little further into the cover than will ordinarily be the case (see Figure 1) and the slot 24 in the sleeve is, for this purpose, made sufficiently long to allow for this additional inward movement of the sleeve. The necessary clearance in the length of the slot just referred to is illustrated at 37 in Figures 1 and 2. A clearance should also be allowed between the outer end of the screw extension 26 and the inner end of the pin 26a.

Figures 6 to 8 illustrate the invention as applied to a post binder comprising upper and lower covers 38 and 39 between which extend binding posts 40, one only of which is shown in Figure 6. The binding posts are fixed at their lower ends in the binding bar 41 of the lower cover 39 and at the upper parts each pass through a hole 42 in the upper binding bar (generally indicated by the reference 43) of the upper cover 38.

In applying this invention to a binder of this character in one arrangement the upper binding bar is made of tubular form and, in the example illustrated, is of a substantially flat rectangular or flattened oval cross-section, the bar being rounded at its longitudinal edges as is clearly shown in the drawing; thus the binding bar is of more or less normal shape. Such a binding bar is adapted either for incorporation in the cover 38 of the binder, as shown in Figure 6, or for use as a separate clamping bar for mounting on the binding posts of a post binder.

The binding bar is closed at one end (the end not shown in the drawings) and is open at the end 44, and between its ends the bar is provided with two or more of the holes 42 through which the binding posts pass. Where it is desired that the binding post should not pass completely through the binding bar as shown in Figure 6, the holes 42 may be provided only in the underside of the bar and not in both sides thereof.

Within the binding bar is arranged a locking slide 45 which is longitudinally slidable in the binding bar. This slide is provided with longitudinally extending upturned flanges 46 which position the slide in the binding bar upon the bottom thereof. The slide is also provided with as many binding post-receiving holes 47 as are provided in the binding bar 43, the arrangement being such that the locking slide can be adjusted so as to have its holes in register with those in the binding bar to enable the binding post to be introduced into the latter, and such that the slide can then be slid endwise relatively to the binding bar in order to lock the latter upon the binding posts.

The means for effecting the longitudinal sliding movement of the locking slide comprise a nut 48 secured, e. g. by welding, within the binding bar 43 and extending transversely thereacross. In this nut is rotatably mounted a screw 49 arranged centrally along the binding bar and having, at its inner end, a reduced neck 50 engaged in a bifurcation 51 provided in an upturned lug 52 furnished at one end of the locking slide 45. Thus when the screw 49 is rotated in the nut 48,

the slide 45 is slid endwise relatively to the binding bar 43 in one direction or the other according to the direction in which the screw 49 is rotated.

5 The end of the screw 49 remote from the locking slide 45 is constructed as hereinbefore described with reference to the thong binder illustrated in Figures 1 to 5. Thus the screw has a sleeve 22 mounted thereon for rotation with the screw but capable of axial movement relatively to the latter, the sleeve carries the coaxial pin 26a and this has mounted thereon a lever similar to the lever 29 previously described and by which the screw is driven, but in this case the said lever is of a slightly different shape and is therefore marked with a different reference numeral, namely 53. In this case the lever is of the same end shape as the binding bar 43 and this bar is made rather shorter than the normal width (from its upper to its lower edge) of the binder cover so that normally the lever 53 will lie within the boundaries of the binder.

20 Figures 6 to 8 illustrate the invention as applied to a post binder comprising upper and lower covers 38 and 39 between which extend binding posts 40, one only of which is shown in Figure 6. The binding posts are fixed at their lower ends in the binding bar 41 of the lower cover 39 and at the upper parts each pass through a hole 42 in the upper binding bar (generally indicated by the reference 43) of the upper cover 38.

25 The lever 53 is furnished with the clutch connection with the sleeve 22 and operates in all respects in the same way as the operating mechanism described with reference to Figures 1 to 5, it only being necessary to withdraw the lever 53 axially away from the binding bar 43 to bring the lever clear of the binder and the sheets bound therein in order to enable the lever to be rotated to release the upper cover of the binder from the binding posts or to clamp the cover upon the latter.

30 Figures 6 to 8 illustrate the invention as applied to a post binder comprising upper and lower covers 38 and 39 between which extend binding posts 40, one only of which is shown in Figure 6. The binding posts are fixed at their lower ends in the binding bar 41 of the lower cover 39 and at the upper parts each pass through a hole 42 in the upper binding bar (generally indicated by the reference 43) of the upper cover 38.

35 The lever 53 is furnished with the clutch connection with the sleeve 22 and operates in all respects in the same way as the operating mechanism described with reference to Figures 1 to 5, it only being necessary to withdraw the lever 53 axially away from the binding bar 43 to bring the lever clear of the binder and the sheets bound therein in order to enable the lever to be rotated to release the upper cover of the binder from the binding posts or to clamp the cover upon the latter.

40 Figures 6 to 8 illustrate the invention as applied to a post binder comprising upper and lower covers 38 and 39 between which extend binding posts 40, one only of which is shown in Figure 6. The binding posts are fixed at their lower ends in the binding bar 41 of the lower cover 39 and at the upper parts each pass through a hole 42 in the upper binding bar (generally indicated by the reference 43) of the upper cover 38.

45 Figures 6 to 8 illustrate the invention as applied to a post binder comprising upper and lower covers 38 and 39 between which extend binding posts 40, one only of which is shown in Figure 6. The binding posts are fixed at their lower ends in the binding bar 41 of the lower cover 39 and at the upper parts each pass through a hole 42 in the upper binding bar (generally indicated by the reference 43) of the upper cover 38.

50 Figures 6 to 8 illustrate the invention as applied to a post binder comprising upper and lower covers 38 and 39 between which extend binding posts 40, one only of which is shown in Figure 6. The binding posts are fixed at their lower ends in the binding bar 41 of the lower cover 39 and at the upper parts each pass through a hole 42 in the upper binding bar (generally indicated by the reference 43) of the upper cover 38.

55 Figures 6 to 8 illustrate the invention as applied to a post binder comprising upper and lower covers 38 and 39 between which extend binding posts 40, one only of which is shown in Figure 6. The binding posts are fixed at their lower ends in the binding bar 41 of the lower cover 39 and at the upper parts each pass through a hole 42 in the upper binding bar (generally indicated by the reference 43) of the upper cover 38.

60 Figures 6 to 8 illustrate the invention as applied to a post binder comprising upper and lower covers 38 and 39 between which extend binding posts 40, one only of which is shown in Figure 6. The binding posts are fixed at their lower ends in the binding bar 41 of the lower cover 39 and at the upper parts each pass through a hole 42 in the upper binding bar (generally indicated by the reference 43) of the upper cover 38.

65 Figures 6 to 8 illustrate the invention as applied to a post binder comprising upper and lower covers 38 and 39 between which extend binding posts 40, one only of which is shown in Figure 6. The binding posts are fixed at their lower ends in the binding bar 41 of the lower cover 39 and at the upper parts each pass through a hole 42 in the upper binding bar (generally indicated by the reference 43) of the upper cover 38.

70 Figures 6 to 8 illustrate the invention as applied to a post binder comprising upper and lower covers 38 and 39 between which extend binding posts 40, one only of which is shown in Figure 6. The binding posts are fixed at their lower ends in the binding bar 41 of the lower cover 39 and at the upper parts each pass through a hole 42 in the upper binding bar (generally indicated by the reference 43) of the upper cover 38.

What I claim is:

1. In a loose leaf binder opening and closing means comprising a screw and a nut rotatable relatively to one another to effect axial movement of the one with respect to the other for

opening or closing the binder, a sleeve mounted on one end of said screw, pin and slot means connecting the said sleeve and screw together for unitary rotation whilst leaving the sleeve and screw capable of relative axial movement, a coaxial headed pin at one end of said sleeve and projecting beyond the end of the sleeve remote from the said screw, an operating lever rotatably and axially adjustably mounted on the said headed pin, clutch means on the inner side of said lever, clutch means on the outer end of said sleeve and adapted to co-operate with said clutch means on the operating lever, and spring means urging said co-operating clutch means into engagement with one another, whereby the said operating lever is normally drivingly connected to said screw in all axially adjusted positions of the said sleeve on the said screw but whereby the operating lever may be disengaged from the said sleeve for rotational adjustment independently of said screw.

2. A loose leaf binder comprising a pair of relatively adjustable covers, means between these covers to carry loose leaves, and means for achieving the adjustment of said covers relatively to one another, such means comprising a rotary screw mounted within one of the binder covers parallel to the major outer surfaces thereof, a nut on said screw, an operating lever for rotating the said screw to produce relative axial movement between the screw and the said nut for binder cover adjusting purposes, a sleeve mounted upon one end of said screw, pin and slot means connecting the said sleeve to the said screw for unitary rotation therewith whilst permitting relative axial movement between the screw and sleeve, a coaxial headed pin at one end of the said sleeve and projecting beyond the end of the said sleeve remote from the said screw and outwardly into a recess provided for housing the said operating lever in an outer edge of the binder cover containing said screw, said operating lever being rotatably and axially adjustably mounted on the said headed pin and capable of being housed in the said recess in the recessed binder cover, clutch means on the inner side of the said lever, clutch means on the outer end of the said sleeve and adapted to co-operate with the clutch means on the operating lever and spring means for urging said co-operating clutch means into interengagement, whereby the said operating lever is normally drivingly connected to said screw in all axially adjusted positions of the said sleeve with respect to the screw but whereby the operating lever may be disengaged from said sleeve for independent rotational adjustment to enable the operating lever to be moved for stowage in the said recess in the recessed binder cover and within the thickness of such cover even if the operating lever does not occupy such a stowed position at the end of any particular operation of the lever.

3. A loose leaf thong binder comprising a pair of relatively adjustable covers between which a bundle of loose leaves may be clamped, a cross bar mounted adjustably within one of the said binder covers, at least two spaced thongs attached at one end to said cross bar and, at the other end, to the other of said covers, a bearing within the same cover as the said cross bar, a rotary screw mounted in said bearing within the same cover parallel to the major outer surfaces of this cover and said screw being restrained against axial movement in said bearing, a nut screwed onto said screw and also attached to said cross bar for movement therewith, an operating lever for rotating the said screw to produce axial movement of the said nut with respect to the screw for binder cover adjusting purposes, a sleeve mounted upon one end of said screw, pin and slot means connecting the said sleeve to the said screw for unitary rotation therewith whilst permitting relative axial movement between the screw and sleeve, a headed pin projecting coaxially from the end of the said sleeve remote from the said screw and extending outwardly into a recess provided for housing the said operating lever in an outer edge of the binder cover containing the said screw, said operating lever being rotatably and axially adjustably mounted on the said headed pin between the head of the latter and the said sleeve and being capable of being housed in the said recess in the recessed binder cover, clutch teeth on the inner side of the said lever, clutch teeth on the outer end of the said sleeve and adapted to co-operate with the clutch teeth on the operating lever and a compression spring disposed between the head of said headed pin and the base of an axial recess provided in the said operating lever, for urging the said co-operating clutch teeth into interengagement, whereby the said operating lever is normally drivingly connected to the said screw in all axially adjusted positions of the said sleeve with respect to the screw but whereby the operating lever may be disengaged from the said sleeve for independent rotational adjustment to enable the operating lever to be moved for stowage in the said recess in the recessed binder cover and within the thickness of such cover even if the operating lever does not occupy such a stowed position at the end of any particular operation of the lever.

ALFRED GILBERT.
